HANGER FOR CLIP-ON TIES

Larman D. Johnson, 1718 N. 17th,
Boise, Idaho 83702

Filed June 29, 1970, Ser. No. 23,718

Term of patent 14 years

Int. Cl. D6—07

U.S. Cl. D80—8

FIG. 1 is a left front perspective view of a hanger for clip-on ties embodying my new design;

FIG. 2 is a right rear perspective view as viewed from the bottom.

I claim:

The ornamental design for a hanger for clip-on ties, substantially as shown.
